UNITED STATES PATENT OFFICE.

CHARLES J. P. HOEHN, OF OAKLAND, CALIFORNIA, ASSIGNEE TO ENTERPRISE FOUNDRY CO., OF SAN FRANCISCO, CALIFORNIA, A CORPORATION OF CALIFORNIA.

BRAKE-SHOE.

1,186,302

Specification of Letters Patent. Patented June 13, 1916.

Application filed March 8, 1916. Serial No. 82,843.

To all whom it may concern:

Be it known that I, CHARLES J. P. HOEHN, a citizen of the United States, residing at Oakland, in the county of Alameda and State of California, have invented certain new and useful Improvements in Brake-Shoes, of which the following is a specification.

My invention relates to an improved brake shoe for car wheels and the like, and resides more particularly in improved means for positioning the shoe with respect to the brake head upon which it is carried. As is well known, brake shoes of this type are subject to rapid wear, and have very heavy strains imposed upon them, so that wear also takes place at the points of connection between the brake shoe and the brake head. This results in the shoe becoming loose upon the head, and may even cause it to become displaced, so that said shoe no longer bears its proper relation to the wheel. A brake shoe in this condition is extremely dangerous, for the reason that its supporting lugs may be cracked or broken by the jarring and strains occasioned by its ordinary use, or the shoe itself may be cracked when forced against the wheel in an abnormal position. In either event the shoe or portions thereof are liable to drop upon the track, in the case of rail-running vehicles, and cause a serious accident.

The object of the present invention, therefore, is to provide means associated with the brake shoe for retaining the same in proper position relative to the brake head and the wheel, even in the event of unusual and excessive wear and looseness between said shoe and said head.

To this end my invention consists in the novel brake shoe fully described hereinafter with reference to the accompanying drawings, in which—

Figure 1 is a rear elevation of the brake shoe attached to a brake head, certain portions of the latter being broken away. Fig. 2 is a part-sectional, side-elevation of the same. Fig. 3 is a transverse section taken on the line $x-x$ of Fig. 2, and viewed in the direction of the arrows, showing my safety lugs bearing against both sides of the brake head. Fig. 4 is a transverse section, similar to Fig. 3, of a modified form of

brake shoe having the safety lug on one side only.

In the drawings, the reference numeral 1 designates a brake shoe, formed of cast iron or other suitable material, and preferably provided with a steel reinforcing strip 2 embedded in its back, said strip having a raised center portion 3 provided with an aperture 4 through which may be placed a suitable key, not shown in the drawings, for attaching the shoe 1 to a brake head 5 in the well known manner.

Embedded in the shoe 1, near each end thereof, and preferably beneath the reinforcement 2, are transversely disposed malleable strips 6 formed of soft steel or other suitable material, the projecting ends 7 of which are bent upward to engage and bear against the side faces 8 of the brake head 5. These up-turned lugs may be bent to conform to brake heads of different widths, as, for example, one which is formed or has been worn narrower than the shoe, as illustrated in the drawings, or in the case of a shoe formed with a groove 9 adapted to overlie the wheel flange, as shown in Fig. 4, the lugs 7 may be employed upon one side only.

The function of the lugs 7 is to maintain the shoe 1 in its proper alignment with the head 5, and therefore in line with the wheel. By making said lugs of malleable steel in the manner shown, they provide guides for the shoe even in case the usual cast guide lugs 10 break or are worn off by the constant jarring of the shoe upon the head, and the shoe is thus held in its proper position.

I do not wish to be construed as limiting myself to the preferred form and construction of the device herein illustrated and described, for the reason that changes may be made therein without departing from the spirit of the invention.

I claim:

1. In a brake shoe having a cast body and means for connection with a brake head, a malleable member cast within said body and having its end projecting outwardly to engage the side of said head to prevent relative lateral movement between said shoe and said head.

2. In combination with a brake shoe having means for connection with a brake head, a malleable lug projecting outwardly from

the back of said shoe and adapted to engage said head to prevent relative lateral movement between said shoe and said head.

3. In a brake shoe having a cast body and means for connection with the brake head, a malleable member cast within said body and having its ends projecting outwardly to form lugs to partially embrace said head to prevent relative lateral movement between 10 said shoe and said head.

4. In combination with a brake shoe having means for connection with a brake head, a pair of spaced malleable lugs projecting outwardly from the back of said shoe and 15 adapted to partially embrace said head to prevent relative lateral movement between said shoe and said head.

5. In combination with a brake shoe having means for connection with a brake head, 20 a malleable strip cast within the body of said shoe with its end projecting from the side thereof, said end being bent to project beyond the back of the shoe and positioned to engage the brake head to prevent relative lateral movement between said shoe and 25 said head.

6. In a brake shoe having a reinforcement in its back and means for connection with a brake head, a malleable strip disposed 30 within the body of said shoe beneath said reinforcement and having its end projecting from the side of the shoe, said end being bent to project beyond the back of the shoe

and positioned to engage the brake head to prevent relative lateral movement between 35 said shoe and said head.

7. A brake shoe having a cast body, a malleable back adapted for connection with a brake head, and a malleable lug projecting outwardly from said back and positioned to 40 bear against the side of said head to prevent relative lateral movement between said shoe and said head.

8. A brake shoe having a body, a malleable back adapted for connection with a 45 brake head, and a malleable strip transversely disposed within said body beneath said back, the ends of said strip projecting from the sides of the body and being up-turned to engage the sides of the head, to 50 prevent relative lateral movement between said shoe and said head.

9. In a brake shoe adapted for connection with a brake head, a malleable strip transversely disposed within said shoe, the ends 55 of said strip projecting from the sides of the shoe and being up-turned to engage the sides of the head, to prevent relative lateral movement between said shoe and said head.

In testimony whereof I have signed my 60 name to this specification in the presence of two subscribing witnesses.

CHARLES J. P. HOEHN.
